UNITED STATES PATENT OFFICE.

PROSPER D. FENN, OF CHICAGO, ILLINOIS.

FOLIO-BINDER.

SPECIFICATION forming part of Letters Patent No. 546,811, dated September 24, 1895.

Application filed April 11, 1894. Serial No. 507,151. (No model.)

To all whom it may concern:

Be it known that I, PROSPER D. FENN, of Chicago, Illinois, have invented certain new and useful Improvements in Folio-Binders, of 5 which the following is a specification.

This invention relates to a binder for periodicals or other publications which are issued in separate parts or numbers; and the object 10 of the invention is to provide a convenient means for binding or fastening the several parts or numbers of a work together into a volume having suitable backs or covers.

In the accompanying drawings, Figure 1 is 15 a perspective view showing a number or series of folios secured in place, one of the folios being open to show the manner of insertion. Fig. 2 is a broken end elevation showing the volume closed. Fig. 3 is an inverted plan view showing in detail the manner of attaching the binding-wires to the stiffener used in the hinge between the covers, and Figs. 4 and 20 5 are sectional details showing two forms of construction of the stiffener.

In the drawings, A A represents suitable covers or cases, which are hinged together by 25 means of the backbone a, the stiffener B, and the paste or glue strip C. The latter is of such width that its margins project beyond the edges of the stiffener to afford means for 30 attaching it to the surfaces of the adjoining ends of the covers A.

D represents binder-wires, of any number 35 desired, which may be flat, round, or oval wires, having their ends hooked or returned, as at d, and securely fastened upon the under sides of the ends of the stiffener B. This may 40 be done in any convenient manner—as, for example, by means of a strip of cloth pasted or glued over the said ends, which may be also set or bound together by glue or other cement.

In the construction shown in Figs. 4 and 5 the returned ends d are shown as bent parallel to the main body of the wires, and the bend 45 is preferably angular, so as to afford room for inserting the leaves of the folio between the binding-wires and the face of the hinge. As shown in Fig. 4, the stiffener terminates at the bend of the binder-wire, while in Fig. 5

the stiffener is shown extended, as at b, its 50 ends being bent at an angle to its body, so as to support the binder-wires free from the face of the hinge. This construction will be preferable whenever a considerable number of parts are to be bound together, and it permits 55 the ready insertion or removal of the parts.

It may be found expedient to embed the returned ends of the wire in the stiffener or to turn down their extremities in the form of prongs adapted to enter the body of the stiffener. I have shown, however, a fold c of the strip C pasted over them, such fold being pierced by the returned ends d of the wire, as clearly shown in Fig. 4.

I claim—

1. In a binder of the class described, the combination with a stiffener forming a portion of the hinge, of a series of binder wires having bodies of a length equal to that of the stiffener and their ends bent or hooked, the 60 extremities embracing the stiffener and permanently secured thereto and means for securing the stiffener to a case or cover whereby the bent ends are inclosed between the stiffener and such case or cover, substantially 65 as described.

2. In a binder of the class described, the combination with a stiffener forming a portion of a hinge piece, of a series of binder wires having their ends returned to embrace the 70 ends of the stiffener and the extremities of the bent ends secured to the back thereof, and a paste strip secured to the stiffener and affording means for attaching the latter to a case or cover, substantially as described.

3. In a binder of the class described, the combination with a stiffener adapted to form a portion of a hinge, of a series of binder wires having their ends bent angularly with reference to the bodies and their extremities returned parallel to the bodies and embracing the ends of the stiffener, a paste strip secured with the body of the stiffener and having its margins extended beyond the edges thereof, and a fold thereof secured over the returned 80 ends of the binder wires, substantially as described.

4. In a binder of the class described, the

combination with a stiffener having its ends up-turned, of a series of binder wires having an angular bend therein toward their ends and their extremities beyond said bends 5 turned parallel to the body and embracing the bent ends of the stiffener and secured to the body thereof, and a paste strip for secur- ing the stiffener to a case or cover, substantially as described.

PROSPER D. FENN.
